UNITED STATES PATENT OFFICE.

JOHN E. RENHOLDT, OF BRIDGEPORT, CONNECTICUT, ASSIGNOR TO DICTAPHONE CORPORATION, OF BRIDGEPORT, CONNECTICUT, A CORPORATION OF NEW YORK.

RECORD-RESURFACING MACHINE.

Application filed July 30, 1927. Serial No. 209,437.

This invention relates to record-resurfacing machines, and more particularly to machines for shaving record-blanks, intended for use with dictation machines.

5 An object of the present invention is to provide improved means for rigidly mounting the record-resurfacing tool so as to prevent vibration thereof, and thus permit a smoother surface to be obtained on the record.

10 Another object of this invention is to provide improved means for quickly and easily locating and locking the record resurfacing tool with respect of the record in proper position for taking a first or preparatory cut of predetermined depth.

15 Another object of the present invention is to provide improved means for automatically advancing the resurfacing tool for one or more finishing cuts of predetermined depth 20 to be taken after the first or preparatory cut has been made.

25 A still further object of the present invention is to provide means for causing the return of both the record-engaging tool and the advancing mechanism therefor to normal position by a single manual operation.

30 Other features and advantages will hereinafter appear.

35 In the accompanying drawings which show one form of the invention, that at present preferred—

Figure 1 is a rear elevation of a record-resurfacing machine made in accordance 40 with the present invention, the resurfacing tool (a shaving knife in this case) being in the position it usually occupies after a record is shaved and before the knife-bar carriage is moved toward the left as viewed, to starting position.

Fig. 2 is a rear view of part of the machine shown in Fig. 1, showing the automatic knife-advancing mechanism in operating position.

45 Fig. 3 is a side view partly in section of the machine shown in Fig. 1, showing the pivotal mounting of the knife-carrier and means for locking the resurfacing tool in the operative position, the knife-advancing mechanism being shown in the position it assumes during a shaving operation.

50 Fig. 4 is a side view partly in section similar to Fig. 3, but showing the parts in the positions they assume when the knife-carriage is swung upwardly preparatory to

being returned to position to start shaving a record.

Fig. 5 is a top plan view of the parts in the positions shown in Fig. 4, and showing the gage-bar and knife-bar mounting in dotted lines to disclose the operative relation between the gage-bar and knife-bar and the record blank when the knife-bar has been set to take a first or preparatory cut.

The shaving machine shown in the accompanying drawings is particularly adapted for shaving or otherwise resurfacing phonograph record blanks, particularly those adapted to be used with dictation machines. It comprises a frame 10 provided with a left-hand standard 11 and right-hand standard 12. Supported between the standards 11 and 12 is a guide rod 13 adapted to receive a carriage 14 whose forward end is provided with a shoe 15 adapted to ride on a rail 16 forming part of the frame 10. The knife-bar carriage 14 extends forwardly and upwardly from the guide-rod 13 to a point above the rail 16 where it is provided with a weight 17 shaped to be conveniently grasped and to act as a hand-piece by means of which the carriage is moved.

55 A mandrel 18 adapted to receive a record-blank 19 is supported on the frame to be traversed by the carriage 14, which is caused to travel on the guide rod 13 and rail 16 relative to the record-blank 19 by a feed-screw 20 engaged by a feed-nut 21 mounted on the carriage 14. The feed-screw 20 is caused to rotate coordinately with the mandrel 18 by an interconnecting belt 22, and these rotatable members are usually actuated by an electric motor (not shown) 60 mounted below the frame 10.

65 Phonograph record blanks are customarily cut or shaved to resurface them for use when it is desired to obliterate an old record before making a new record on the surface of the blank. This operation may also be accomplished by means of burnishing tools and other arrangements, and so far as some of the salient features of the present invention are concerned, it is immaterial whether the record-engaging tool used be a 70 knife, a burnisher, or other device. However, since the method of cutting is the one most frequently used and most preferable at present, means for that purpose is illustrated 75 herein.

95

100

105

110

- Accordingly, the machine shown in the accompanying drawings comprises a knife-bar 23 adapted to carry at its forward end a knife 24 usually formed of sapphire or other hard stone. This knife-bar 23 is mounted on the carriage 14 and is adapted to be moved so as to bring the knife 24 into contact with the record-surface, so that simultaneous rotation of the record and travel of the knife with the knife-bar carriage 16 while the knife is in engagement with the record causes the top surface of the record to be removed. The knife is preferably provided with a chip-chute 25 into which the shavings from the record pass and through which they fall downwardly through a trough 26 on the frame 10 to a suitable container provided for the purpose of receiving the chips.
- The above described structure and mechanism is common to record-resurfacing machines heretofore manufactured and used and form a part of the present invention only in so far as they are operatively related to or combined with other mechanisms hereinafter described.

In order that the knife 24 may be quickly and easily set to proper operating position for taking the first or preliminary cut when resurfacing a record-blank, the present invention provides improved means whereby a direct manual operation, requiring no special attention on the part of the operator, causes the knife-bar to be so set that the knife will extend into the record-surface only a predetermined and set amount, whereby the layer of record material removed will be of predetermined thickness.

This improved means, according to the present invention, comprises a gage-bar 27 mounted in a housing 28 for the knife-bar and adapted to slide parallel therewith. The knife-bar 23 and gage-bar 27 are tied together by a yoke or tie-bar 29 for movement en bloc in the housing 28 toward and from the record-surface, so that, when they are moved forwardly toward the record-blank, the front face 30 of the gage will engage the record-surface and limit the extent of forward movement of the knife 24 beyond the record-surface. The knife-bar 23 and the gage-bar 27 and yoke are usually so interconnected and formed that the working surface of the knife 24 usually extends beyond the working surface 30 of the gage-bar 27 by an amount equal to substantially fifteen thousandths of an inch. This, with an additional advance of five thousandths of an inch effected by means hereinafter described, represents the depth of a first or preliminary cut.

It is sometimes desirable, however, to change the depth of cut determined by the gage 27, and this is accomplished according to the present invention by providing on the

gage 27 a screw-threaded portion 31 adjustable in a threaded section 32 of the tie-bar 29 connected to the knife-bar 23. These parts are locked in the adjusted position by a threaded disc 33 which preferably has a cupped section 34 which acts as a finger-piece by means of which the gage-bar and the knife-bar are moved toward the record 19.

In adjusting the gage-bar 27 relative to the knife 24, the disc 33 is first turned to release the screw portion 31 and the latter is then turned in the yoke, either to the right or left, until the desired setting is obtained, whereupon the disc 33 is turned to lock the gage-bar 27 against movement in the yoke 29. By this means, a person of ordinary mechanical skill can vary the relation between the gage-bar and the knife-bar so that the depth of cut may be changed to meet prevailing conditions.

The gage-bar, having been set relative to the knife to suit average conditions, these parts are moved from normal inoperative position to a position for taking the first or roughing cut on a record-blank 19 by the operator pressing his finger against the finger-piece 34 carried by the gage-bar until the flat end 30 of the gage-bar comes in contact with the record-surface, at which time the edge of the knife will be located forwardly of the record a predetermined amount.

In making the shaving machine, the gage-bar 27 may, of course, be located at either side of the knife-bar 23, depending upon what point in the operation of the machine it is desired to set the knife-bar 23. It is considered preferable, at present, to place the gage-bar 27 behind the knife-bar 23, considering the direction of travel of the carriage while the knife is cutting, so that the gage-bar end 30 will always be above and spaced from the record-surface just shaved by the knife 24. Moreover, when so placed, the gage-bar may be arranged to contact with the record, when setting the knife, while the knife is located beyond the end of the record at the finish position of cutting travel, as seen in Fig. 5. Hence, the knife-bar and gage may be moved into position by hand as above described, without necessitating the pressing or forcing of the knife 24 into the record-surface. After this setting, the carriage is pivotally moved on the guide-rod 13, then slid to starting position for cutting travel at the left side of the machine shown in Fig. 1, so the gage-bar end will trail the knife 24 and be spaced from the shaved record-surface a distance substantially equivalent the depth of cut taken as the cutter travels over the record-surface toward the finish positions.

The present invention also provides improved means for locking the knife-bar 23

in any manually adjusted position so that it will be firmly held in that position while shaving a record. This means, in the form shown in the accompanying drawings, comprises a shaft 35 mounted to rotate in the housing 28 adapted to extend transversely of the knife-bar 23. The shaft 35 is provided with a cam section 36 adapted to engage a flat surface 37 on the bottom of the knife-bar 23 so that, when the shaft 35 is rocked by a spring 38 (Fig. 1), the cam section 36 will be brought into engagement with the flat surface 37 on the knife-bar to firmly lock the knife-bar in place. The cam section 36 is so arranged that should the knife-bar 23 tend to move backwardly, it would cause the shaft 35 to be rocked, thereby causing the cam 36 to move tightly and firmly engage the knife-bar and prevent its further movement.

In order to advance the knife 24 step-by-step to take finishing cuts, it has previously been proposed to slide the knife-bar and carrier therefor on the carriage to and from the record. It has also been proposed to allow falling movements of the carriage itself step-by-step to accomplish this purpose.

According to the present invention, however, the step-by-step advancement of the knife 24 is accomplished by pivotally moving the knife-bar on the carriage, as distinguished from pivotally moving the knife-bar with the carriage. Accordingly, the knife-bar carrier 28 of the present invention is pivotally mounted on a rod 39 carried in a pair of ears 40 and 41 formed integral with the carriage 14 and between which ears the end 42 of the cutter carrier 28 snugly fits. The shaft 39 is arranged parallel to the axis of the mandrel 18 so that when the cutter carrier 28 is rocked on the shaft, the knife 24 will be moved toward or from the record, according to whether the knife-carrier 28 is given a clockwise or counter-clockwise movement, as seen in Fig. 3.

Normally, the knife-bar housing 28 is urged rearwardly, that is to say, away from the mandrel 18, by means of a spring 43 which is located in the carriage 14 and which forces a plunger 44 upwardly against a forwardly extending arm 45 on the cutter-carrier 28. It is against the tension of the spring 43 that the cutter-carrier 28 is advanced step-by-step to move the knife 24 closer to the record 19 for successive finishing cuts.

This step-by-step movement of the cutter-carrier 28 is controlled by a cam disc 46 mounted on a stud 47 on the carriage 14, cooperating with a roller 48 mounted on a stud 49 carried by the arm 50 of the cutter carrier 28. The spring 43 normally urges the knife-bar housing 28 rearwardly so that the roller 48 contacts with the surface of the cam disc 46.

The cam disc 46 is provided with a series of ratchet teeth 51 adapted to be engaged by a feed pawl 52 pivotally carried by a pawl-arm 53 pivotally mounted on a stud 54 carried by the carriage 14. The ratchet teeth 51 are also engaged by a back-check pawl 55 pivotally mounted on the stud 54 and normally urged by the weight of its arm 56 into engagement with the ratchet teeth to prevent backward movement of the cam disc 46 against the tension of a spring 57 located in an undercut portion in the stud 58, see Fig. 4.

In order that the cam disc 46, and hence the knife 24, may be moved step-by-step to accommodate for successive finishing cuts as an incident to the movement of the carriage to position to start shaving a record, the arm 53 of the feed pawl 52 is arranged to overlie a projection 59 on the base plate 10 when the carriage is, as is shown in Fig. 1, in the position at the end of a shaving operation. The parts are so arranged that when the carriage 14 is raised by means of the hand-piece 17 from the positions shown in Figs. 1 and 3 to that shown in Figs. 2 and 4, the lower portion of the pawl arm 53 engages the projection 59 on the frame and causes the pawl 53 to engage a ratchet tooth on the cam disc 46 and move the latter an amount equal to the distance between two teeth, the pawl 52 at this time moving clockwise, as seen in Figs. 1 and 2, against the tension of its spring 60. While the cam disc 46 is being so moved, one of the ratchet teeth thereon passes the back-check pawl 55 and the latter then prevents the cam disc 46 from rotating backwardly until the desired time.

This upward swinging movement of the carriage 14 is necessary to permit the movement of the carriage to starting position, for by it the feed-nut 21 is removed from the feed-screw shaft 22, as shown in Fig. 4, and the knife 24 and gage 27 are moved away from the record. With the carriage so raised, it is moved longitudinally of the machine toward the other end of the record and, upon reaching that end, it is allowed to descend to cause the knife 24 to engage the record 19 and shave the same.

During the movement of the carriage to starting position, the feed-pawl arm 53 slides off the projection 59 and is returned to its normal position by a spring 61 wrapped around the stud 54 and having one end anchored in the pawl arm 53 while the other end is anchored in the carriage 14.

If the first finishing cut is not sufficient to provide a satisfactory recording surface on the record, additional finishing cuts may be obtained by again raising the carriage 14 and moving it to starting position. Thus, without making any manual readjustments of the knife, the automatic advancing means, comprising the feed-pawl 52 and cam disk 130

46 above referred to, will advance the knife by moving the knife-carrier 28 arcuately toward the record during the raising of the carriage.

- 5 After the record has been satisfactorily shaved, it is desired to return the knife 24 and knife-bar carrier 28 with the step-by-step advancing means, comprising the cam disc 46, to normal position so that the knife 10 may be manually set to take a first or preparatory cut from a new record. To do this, the shaft 35, which has the cam surface 36 which locks the knife-bar 23 in the knife-bar housing 28 against movement, is provided 15 with a lever 62 secured thereto and adapted to be manually operated to rotate the shaft 35 against the tension of the spring 38 to thus release the knife-bar 23. When so released, the knife-bar 23 is restored to 20 operative position by means of a spring 63 located in the housing 28 between the housing and a collar 64 on the gage-bar 27. At the same time, the knife-advancing cam disc 46 is released so as to permit its return by 25 the spring 57 (see Fig. 4) by causing the back-check pawl 55 to be disengaged from the ratchet teeth 51.

This is accomplished without requiring attention on the part of the operator by providing a connection between the weight arm 56 of the back-check pawl and an arm 65 on the knife-bar lock lever 62, comprising a lug 66 on the weight lever 56 of the back-check pawl adapted to extend into an aperture 67 30 on the knife-release lever constituting this connection. Hence, when the knife-release lever 62 rotates with the shaft 35, the arm 65 thereon will raise the arm 56 of the back-check pawl lever 55 and remove the pawl 40 from engagement with the ratchet teeth. By this operation, the cam disc 46 is permitted to be returned to normal or initial position by the spring 57, because the feed pawl 52 is normally out of engagement with the 45 ratchet teeth 51. When the cam disc 46 is returned to normal or initial position, it allows the knife-housing 28 to be swung to its normal or initial position by means of the 50 spring 48 provided for the purpose. The extremes of movement of the cam disc 46 is limited in both directions by a stop pin 68 engaging shoulders 69 on the cam disc.

The preparatory pivotal upward movement of the carriage 14, when moving the carriage to position to start shaving, is limited according to this invention by an arm 70 55 mounted on the carriage engaging a rail 71 provided on the base 10. The movement permitted by the arm 70 and rail 71 is, of course, more than sufficient to move the knife-bar 60 out of engagement with the record and the feed-nut 21 out of engagement with the feed-screw 20, but it is just sufficient to move the knife-advancing means the proper or 65 requisite amount.

In order to insure that the carriage is raised sufficiently high to move the knife-advancing means the proper amount, the present invention provides a pair of escapement lugs 72 and 73, the lug 72 being mounted on the carriage 14 and the lug 73 being mounted on the frame 10. These lugs are normally arranged to be in the relative positions shown in Figs. 1 and 3 when the carriage is at the end of a shaving operation. In this 75 position, the lug 72 is beyond the lug 73 and hence the carriage may be swung upwardly without interference with the lug 73. Should the carriage be swung up partially, however, and not far enough to operate the 80 knife-advancing means, the lug 72 will be in position to be engaged by the lug 73 should an attempt be made to move the carriage longitudinally. However, if the carriage is moved sufficiently, the lug 72 is carried 85 forwardly beyond the lug 73, as shown in Fig. 4, and in this position longitudinal movement of the carriage is permitted.

It will be understood that the relative setting of the knife-bar 23 and the gage-bar 90 27 is such that the amount of the first cut will be the sum of the amount by which the knife-bar protrudes beyond the gage-bar and the amount of advancement given to the knife by the means for advancing the knife 95 for a secondary cut, for the automatic knife-advancing means operates when the carriage 14 is first raised after setting the knife by hand as well as during subsequent raising movements of the carriage as when taking 100 successive finishing cuts.

Variations and modifications may be made within the scope of this invention and portions of the improvements may be used without others.

Having now described the invention, what is claimed as new and for which it is desired to obtain Letters Patent, is:—

105

1. In a record-resurfacing machine, the combination of a mandrel for supporting a record to be resurfaced; a carriage; a tool-carrier pivotally mounted on the carriage; an interconnected record-engaging tool and gage mounted in the tool-carrier; and self-tightening means for locking the record-engaging 110 tool in desired relationship with the record.

2. In a record-resurfacing machine, the combination of a mandrel for supporting a record to be resurfaced; a carriage; a cutter-carrier pivotally mounted on the carriage; a 115 cutting tool; a gage interconnected with the tool to predetermine the depth of cut of the tool; and means for adjustably varying the depth of cut determined by said gage.

3. In a record-resurfacing machine, the 120 combination of a mandrel for supporting a record to be resurfaced; a carriage; a tool-carrier; a record-engaging tool and a gage 125 interconnected and supported in the tool-carrier, said tool-carrier being pivotally mounted 130

on the carriage for arcuate movement toward and from a record supported by the mandrel; and automatic means operable while the carriage is located at the end of its travel for 5 pivotally moving the tool-carrier to advance the record-engaging tool to position to perform a finishing operation on the record.

4. In a record-resurfacing machine, the combination of a mandrel for supporting a 10 record to be resurfaced; a carriage; a cutter-carrier; a record-cutting tool and a depth-of-cut gage interconnected and supported by the cutter-carrier, the latter being mounted on the carriage for arcuate movement toward 15 and from a record supported on the mandrel; and automatic means operable while the carriage is located at the end of its travel after taking a cut of predetermined depth for moving the cutter-carrier arcuately to advance the 20 record-cutting tool to position to take a finishing cut of predetermined depth.

5. In a record-resurfacing machine, the combination of a mandrel for supporting a record to be resurfaced; a carriage mounted 25 for movement to carriage-returning position; a record-engaging tool mounted on the carriage; means operable as an incident to the movement of the carriage to carriage-returning position while the carriage is located at 30 the end of its travel for advancing the record-engaging tool to a position to take a cut of predetermined depth; and means necessitating the completion of the movement of the carriage to carriage-returning position before 35 the carriage is permitted to return to position to start said cut of predetermined depth.

6. In a record-resurfacing machine, the combination of a mandrel for supporting a record to be resurfaced; a carriage mounted 40 for pivotal movement; a record-cutting tool mounted on the carriage; means operated as an incident to the pivotal movement of the carriage while the carriage is located at the end of its travel for advancing the record- 45 cutting tool to a position to take a cut of predetermined depth; and means preventing return of the carriage to position to start said cut of predetermined depth until the completion of the pivotal movement of the carriage is sufficient to cause advancement of the 50 record-cutting tool.

7. In a record-resurfacing machine, the combination of a mandrel for supporting a record to be resurfaced; a carriage mounted 55 for pivotal movement; a record-cutting tool mounted on the carriage; means operated as an incident to the pivotal movement of the carriage while the carriage is located at the end of its travel for advancing the record- 60 cutting tool to a position to take a cut of predetermined depth; and a blocking arm mounted in position to be engaged by the carriage to block its returning movement until the carriage has been pivotally moved 65 sufficiently far to cause the operation of the

means for advancing the record-cutting tool.

8. In a record-resurfacing machine, the combination of a frame; a mandrel for supporting a record to be resurfaced; a carriage 70 mounted on the frame for pivotal movement; a record-cutting tool mounted on the carriage; means operated as an incident to the pivotal movement of the carriage while the carriage is located at the end of its travel 75 for advancing the record-cutting tool to a position to take a cut of predetermined depth; and cooperating means mounted on the carriage and mounted on the machine and adapted to prevent longitudinal movement of the carriage in returning direction from the said end of its travel until when the carriage has been pivotally moved sufficiently far to operate said means for advancing the record-cutting tool. 80

9. In a record-resurfacing machine, the combination of a mandrel for supporting a record to be resurfaced; a carriage; a cutter-carrier pivotally mounted on the carriage; means for arcuately feeding the cutter-carrier 90 toward the side of the record incidental to the movement of the carriage to position for starting a new or finishing cut; manually operable means for freeing the cutter-carrier to return to normal position and means for 95 returning the cutter-carrier to normal position incident to the release of said manually operable means.

10. In a record-resurfacing machine, the combination of a mandrel for supporting a 100 record to be resurfaced; a carriage; a tool-carrier pivotally mounted on the carriage; a record-engaging tool; means for positively locking the record-engaging tool in the pivotally mounted tool-carrier; automatic 105 means for pivotally advancing the tool-carrier toward the record for successive finishing cuts incident to the movement of the carriage from finishing position of travel to the starting position of travel; and means for 110 simultaneously returning the record-engaging tool, the tool-carrier, and the tool-carrier advancing means to normal positions by the release of said means for locking the record-engaging tool. 115

11. In a record-resurfacing machine, the combination of a mandrel for supporting a record to be resurfaced; a carriage; a tool-carrier pivotally mounted on the carriage; a record-engaging tool; manually operable 120 means for locking the record-engaging tool with relation to the record being resurfaced; means for advancing the tool-carrier toward the side of the record for successive finishing cuts; and means for simultaneously accomplishing the return of the record-engaging tool, the tool-carrier, and the tool-carrier advancing means to normal positions by the release of said manually operable means, said means being operable in any position of the 125 record. 130

pivotsally mounted tool-carrier on the carriage.

12. In a record-resurfacing machine, the combination of a mandrel for supporting a record to be resurfaced; a carriage; a tool-carrier pivotally mounted on the carriage; and a record-engaging tool and depth-of-cut gage slidably mounted in the pivotally mounted tool-carrier for simultaneous movement toward and from the record.

13. In a record-resurfacing machine, the combination of a mandrel for supporting a record to be resurfaced; a carriage; a cutter-carrier pivotally mounted on the carriage; a cutter-carrier feeding mechanism comprising a cam and ratchet wheel segment on the carriage for arcuately advancing the cutter-carrier toward the side of the record; and a roller mounted on the cutter-carrier contacting and turning with the movement of the cam surface of the cam and ratchet wheel segment.

14. In a record-resurfacing machine, the combination of a mandrel for supporting a record to be resurfaced; a top plate; a carriage pivotally mounted on the top plate; a cutter-carrier pivotally mounted on the carriage; and a cutter-carrier feed means comprising a cam and ratchet wheel segment actuated by a pawl, the said pawl being mounted on a plate which engages the top of a boss on the top plate when the carriage

is pivotally moved, this movement of said means causing the pawl to engage the ratchet wheel segment and advance one step of the 35 cam and ratchet wheel segment, and causes the arcuate movement of the cutter-carrier toward the record.

15. In a record-resurfacing machine, the combination of a mandrel for supporting a record to be resurfaced; a carriage; a tool-carrier pivotally mounted on the carriage; a record-engaging tool mounted on said tool-carrier; means for locking the record-engaging tool against movement in the tool-carrier; feeding means for the tool-carrier comprising a cam and a ratchet wheel segment to pivotally move the tool-carrier step-by-step toward the record; back-check means to engage the teeth on the ratchet-wheel segment 50 to hold it in the position to which it is moved; and means coupling the tool-locking means and the back-check means for simultaneous release to allow the return to normal position of the tool, the tool-carrier and the 55 tool feed means when the tool-locking means is released, said coupling being loose to permit the operation of the back-check means when the feed-means is actuated and independently of the tool-locking means. 60

Signed at Bridgeport, in the county of Fairfield, and State of Connecticut, this 26th day of July, 1927.

JOHN E. RENHOLDT.
